(57) **CLAIM**

The ornamental design for a kiosk for processing electronic devices, as shown and described.

DESCRIPTION

FIG. 1 is a front right top perspective view of a kiosk for processing electronic devices showing a first embodiment of our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dashed broken lines shown in the Figures represent portions of the kiosk for processing electronic devices that form no part of the claimed design. The dot-dash broken lines define the bounds of the claimed design and form no part thereof.

While the accompanying drawings include broken lines that form no part of the claimed design, the broken lines provide written description of prospective embodiments that are claimed when one or more of the broken lines are amended to solid lines. Similarly, while the solid lines in the drawings form part of the claimed design, the solid lines provide written description of prospective embodiments that are not claimed when one or more of the solid lines are amended to broken lines.
